UNITED STATES PATENT OFFICE.

CHARLES MANSHEL, OF NEWARK, NEW JERSEY.

TICKET STAMPING AND PRINTING MACHINE.

Application filed September 9, 1922. Serial No. 587,187.

To all whom it may concern:

Be it known that I, CHARLES MANSHEL, a citizen of the United States, residing at Newark, in the county of Essex and State of New Jersey, have invented certain new and useful Improvements in Ticket Stamping and Printing Machines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to a ticket stamping or printing machine; and the invention has reference, more particularly, to a machine of simple construction for use in ticket offices for printing portraits of the purchasers upon railroad tickets, and for similar uses.

It has long been desired by railroad companies to provide passenger tickets, especially commutation tickets and the like, with a means in connection with the ticket itself whereby the holder of the same may be readily and quickly identified as the rightful original purchaser of the same. To this end railroad companies have required commutators to furnish photographs of themselves from which copies were made and pasted or similarly affixed to the tickets issued to them. Frequently the photographs so affixed would tear off or become so mutilated as to be unrecognizable, and consequently the purpose they were intended to fulfill was not served. A need has therefore arisen for a more permanent method of applying such photographs to the tickets. Such need would be served by printing the photograph directly upon the surface of the ticket, provided a convenient and simple means was provided, suitable for installation in local ticket offices and capable of being easily operated by the ticket agents without necessity of exercising any great amount of mechanical skill either in the actuation or the care thereof.

It is therefore the object of this invention to provide a simple and easily actuated stamping or printing mechanism which will serve the purposes above indicated.

Other objects of the invention, not at this time more particularly enumerated, will be clearly understood from the following detailed description of the same.

With the various objects of this invention in view, the same consists, primarily, in the novel stamping or printing machine herein-after set forth; and the invention consists, furthermore, in the novel arrangements and combinations of the various devices and parts, as well as in the details of the construction of the same, all of which will be hereinafter more fully described in the following specification, and then finally embodied in the claims appended thereto.

The invention is clearly illustrated in the accompanying drawings, in which:—

Figure 1 is a front elevation of the novel stamping or printing machines made according to and embodying the principles of this invention; Figure 2 is a vertical longitudinal cross section through said machine, taken on line 2—2 in said Figure 1; Figure 3 is a front elevation of the machine illustrating the operation of the type-plate inking means; Figure 4 is a similar front elevation illustrating the operation of the stamp or impresser member in the act of printing; Figure 5 is a detail horizontal section, taken on line 5—5 in Figure 1, showing the ink carrying or feed rollers; Figure 6 is a detail horizontal section, taken on line 6—6 in Figure 1, showing the ink transfer rollers and the carriage therefor; and Figure 7 is a detail vertical transverse section, taken on line 7—7 in Figure 2, showing the type-plate gripping devices of the stamp or impresser member.

Similar characters of reference are employed in all of the hereinabove described views, to indicate corresponding parts.

Referring now to said drawings, the reference character 10 indicates a suitable base, extending upwardly from which is a guide-frame 11. Said guide-frame 11 is provided with a vertical guide-way 12, and adjacent to the base 10 with a horizontal guideway 13. The upper end of said guide-frame 11 is provided with a bearing portion 14, in which is mounted, for rotation therein, a shaft 15. Fixed on the forward end of said shaft 15, in front of said guide-frame is a stamp actuating cam 16, adapted to be rotated by said shaft. Preferably said cam is provided on each side with a cam-groove 17. Vertically reciprocable in said vertical guide-way 12 is a stamp or impresser bar 18. The upper end of said stamp or impresser bar 18 is cut away to provide a cam-way 19, which

permits said upper end of said stamp or impresser bar 18 to straddle the perimeter of said cam 16. Suitably affixed to the opposite walls of said cam-way 19 are inwardly projecting studs 20 and 21 upon which are mounted anti-frictional rollers 22 and 23, which in turn are respectively operatively engaged in the respective cam-grooves 17 at the opposite sides of said cam 16, all whereby said stamp or impresser bar 18 is related to said cam 16 so as to be reciprocated by the rotation thereof. Connected with the lower end of said stamp or impresser bar 18 is a stamp-foot 24, to the underside of which may be detachably affixed the half-tone printing plate 25 or other type element, by means of which the desired picture is to be stamped or printed on a ticket. In order to furnish a means for quickly and easily attaching interchangeable printing plates 25 to said stamp-foot 24, the former are provided at their respective sides with lips 26 of reduced thickness. Secured upon one side of said stamp-foot, in fixed relation thereto, is a clip-plate 27 having a downwardly spaced inwardly projecting retaining lip 28. Secured upon the opposite side of said stamp-foot 24, is a downwardly extending spring-plate 29, the lower end of which is formed to provide a releasable clip-plate 30, also having a downwardly spaced inwardly projecting retaining lip 31. The spring tension of said spring-plate 29 normally tends to swing the lower end of the same outwardly away from the side of said stamp-foot, to move said clip-plate 30 and its retaining lip 31 to released position, as shown by the dotted representation of said parts in Figure 7. Said normal tension of the spring-plate is overcome by a pull-spring 32 which is suitably attached to a finger-piece 33 connected with the clip-plate 30 to extend inwardly through a transverse opening 34 provided in said stamp-foot, the opposite end of said spring 32 being suitably anchored by any convenient means. As shown in Figure 7, the printing-plate 25, when in attached relation to the stamp-foot 24, has its lips 26 respectively engaged by the respective retaining lips 28 and 31 of the respective clip-plates 27 and 30, whereby the printing plate is securely held against the underside of said stamp-foot and operatively coupled therewith. When it is desired to remove one printing-plate and interchange the same for another, the finger-piece 33 is pulled outwardly, whereby the pull of spring 32 upon the spring-plate 29 is relaxed, thus permitting the normal tension of the latter to swing outwardly the clip-plate 30 to thereby remove the retaining finger 3, from engagement with the one lip 26 of the printing plate, whereupon the opposite lip of the latter may be withdrawn from the embrace

of the retaining lip 28 of the opposite clip-plate 27. A reversal of such operation is carried out in coupling the new printing-plate to the stamp-foot.

Secured upon the upper surface of said base 10, in front of said guide-frame 11 and vertically alined beneath said stamp-foot 24, is a platen block 35. This platen block 35 is preferably made of a more or less resilient or yieldable material, such as rubber, leather or the like. The ticket 36, which is to be stamped or printed, is laid across the top of said base 10 to extend over said platen-block 35. Suitable vertical gauge pins 37 are fixed in said base 10 to gauge the position of the ticket, and at one end of the base 10 is fixed a stop-clip 38, which holds the ticket against endwise movement. Fixed upon said guide-frame to extend forwardly over the base 10, and suitably spaced upwardly therefrom, are retaining fingers 39 under which the ticket is engaged, to further aid in properly holding the ticket against movement during the stamping or printing operation.

Mounted in connection with said guide-frame 11, at one side of said stamp or impresser bar 18, is an ink carrying or feeding means, the same comprising a main ink carrying roll 40, the rearward end of the shaft 41 of which is journaled in said guide-frame, while the forward end of said shaft is journaled in a depending outwardly offset bearing arm 42 of a bearing clip 43 affixed to the guide-frame. Secured upon the rearward end of said shaft 41 is a sprocket wheel 44, which is driven by a chain 45 running from a drive sprocket 46 fixed on said main shaft 15, all so as to rotate said ink carrying roll 40. Mounted at one side of said ink carrying roll 40 so as to rotate in contact with the surface thereof is an ink spreading roll 47 suitably journaled between said guide-frame 11 and a second depending outwardly offset bearing arm 48 connected with said bearing clip 43. In order to assure a proper spreading and distribution of the ink upon the entire surface of said carrying roll 40, and also to assure a thorough even feeding of the same to ink transfer rolls to be subsequently described, means are provided to longitudinally reciprocate said carrying roll 40 during and in addition to its rotative movement. The means for producing such longitudinal reciprocations comprises a cam projection 49 fixed to the inner end of said carrying roll, which is adapted to cooperate with a fixed stud 50 projecting outwardly from the guide-frame 11. Spring means, such as the springs 51 or equivalent devices, are provided to thrust the roll 40 endwise in an inward direction so as to maintain the cam-projection 49 in constant operative relation to the stud 50. From an inspection

of Figures 1 and 5, more particularly it will be quite apparent, that as the carrying roll 40 is rotated it will longitudinally slide back and forth relative to and in contact with the surface of said spreading roll 47, whereby the ink from time to time deposited on said carrying roll will be thoroughly and smoothly worked out over the entire surface of the same, while at the same time the carrying roll will also be caused to smoothly and evenly distribute the ink upon the ink surface rolls, as will presently appear. The carrying roll 40 and the spreader roll 47 may be made of any material suitable to the functions of ink carrying and spreading.

In order to assure a proper inking of the printing plate 25 coupled to the stamp-foot 24, prior to the downward printing or stamping stroke of said stamp-foot, an automatic and properly timed ink transferring means is provided, whereby the ink is efficiently transferred from said carrying roll 40 to the printing plate. This means comprises a slide-block 52 which is mounted to reciprocate horizontally back and forth in said horizontal guide-way 18 of said guide-frame. The means for producing a properly timed reciprocation of said slide-block 52 consists of a pivoted bell crank lever 53 fulcrumed at 54 upon the rear face of said guide-frame 11. The lower arm of said bell-crank lever 53 is pivotally interconnected by a link 55 with the rear side of said slide-block 52. Fixed on said shaft 15 in the rear of said guide-frame is an inker cam 56 provided in its front face with a suitably shaped cam groove 57. The upper arm of said bell-crank lever 53 is provided with a stud 58 upon which is journaled an anti-friction roller 59 which rides in and is operatively engaged by said cam groove 57 to produce the properly timed oscillations of said bell-crank lever, which in turn produces the desired timed reciprocation of said slide-block 52 and the ink transfer means carried thereby. The ink transfer means consists of a bearing frame or yoke 60 pivotally connected at its rear end for vertical swing. When said slide block 52 is in normal initial position said bearing frame or yoke 60 extends horizontally beneath said ink carrying roll 40 and said spreading roll 47. Journaled to extend transversely between the free ends of said bearing frame or yoke 60 are a pair of inking rollers 61 and 62. Projecting rearwardly from the pivoted end of said bearing frame or yoke 60 is an arm 63. Said slide block 52 is provided at its rearward end with a rearwardly projecting tail-piece 64, and interconnected between said tail-piece and the free end of said arm 63 is a spring 65 which tends to tip upwardly the bearing frame or yoke 60 to yieldably engage the rollers 61 and 62 with the ink carrying roll 40, and to also yield-

ably press the inking rollers 61 and 62 against the printing-plate 25 when the same are carried forwardly over the latter. The said inker cam 56 is so set on the shaft 15 relative to the position of said stamp actuating cam 16, that it operates to move the slide-block 52 forward and back to carry the inking rollers across the face of the printing plate 25 while the stamp actuating cam 16 is rotating through its inactive portion, and before the active portion of the latter produces the stamping or printing stroke of the stamp or impresser bar 18, all of which will be understood more particularly from an inspection of Figures 1, 3 and 4. Fixed on the rearward end of said shaft 15 is a balance or fly wheel 66 to which is connected a handle 67 by means of which the wheel and shaft may be turned to actuate the mechanism.

The operation of the machine is very simple; the ticket having been placed in position over the platen-block 35, and the selected printing plate 25 coupled with the stamp-foot 24, the operator merely imparts to the shaft 15, by means of the wheel 66 and handle 67 one revolution, whereby the cams 16 and 56 are rotated to actuate the inking and stamping devices. During such revolution the active portion of the inker cam 56 is first rotated into actuating engagement with the bell-crank lever 53, whereby the slide-block 52 is caused to move forward and back, thereby moving the inking rolls 61 and 62, which have received a coating of ink from the carrying roll 40, across and in contact with the printing face of the printing plate 25 so that the ink thus carried by the inking rolls 61 and 62 is transferred to such printing face, this operation being illustrated in Figure 3 of the drawings. By the time the slide-block 52 and the inking rolls associated therewith are retracted to normal initial position, the active portion of the cam 16 rotates into actuating relation to the stamp or impresser bar 18, causing the same to slide downward and thereby forcibly impress the printing plate upon the face of the ticket, the platen-block yielding to the pressure while at the same time assuring a perfect contact of the entire printing surface of the printing plate with the ticket. While the cam 16 is thus rotating through its active portion, the inker cam 56 is rotating through its inactive portion, and upon the completion of one revolution of the shaft 15, said cams 16 and 56 together with the parts actuated thereby are returned to normal initial positions ready for another operation.

It will be understood from the above description, that the mechanism is of simple character, requiring very little mechanical knowledge for its operation and care, and being so positively timed by the action of

the cams, as to be efficiently automatic, all of which renders the same ideal for use in ticket offices and for similar uses having in view the stamping or printing of desired

5 matter.

As will also be understood any desired number of printing plates may be employed, the same being readily and quickly interchangeable relative to the stamp-foot by the 10 actuation of the simple yet efficient coupling means provided for the purpose.

I am aware that some changes may be made in the construction of stamping or printing apparatus above described without

15 departing from the scope of the invention as set forth in the above specification and as defined in the claims. Hence, I do not limit my invention to the exact arrangements and combinations of the various devices and 20 parts as described in the said specification, nor do I confine myself to the exact details of the construction of the various parts as illustrated in the accompanying drawings.

I claim:

25 1. A device of the kind described, comprising a supporting frame, an impresser bar vertically reciprocable on said frame, a fixed yieldable platen block vertically alined beneath said impresser bar, means for detachably coupling a printing plate on the lower end of said impresser bar, a shaft journaled in said frame, means for rotating said shaft, a rotary ink carrying roll, transmission means between said carrying roll and said 30 shaft, a slide-block horizontally reciprocable on said frame, a spring pressed pivoted yoke frame connected with said slide-block, ink transfer means mounted on said yoke frame to normally engage said carrying roll, a lever mechanism for reciprocating said slide-block, and cam devices on said shaft respectively adapted to 35 actuate said lever mechanism and said impresser bar in timed relation whereby said slide block is moved to engage said ink transfer means with a printing plate fixed on said impresser bar in advance of the operative stroke of the latter.

40 2. A device of the kind described, comprising a base, a guide frame having a vertical guideway and a horizontal guideway intersecting the lower end of said vertical guideway, an impresser bar vertically reciprocable in said vertical guideway, means 45 for detachably coupling a printing plate with said impresser bar, ink transfer means transversely reciprocable in said horizontal guideway, a rotatable shaft journaled in the upper end of said guide frame, cam devices on said shaft respectively adapted to 50 actuate said ink transfer means and said impresser bar in timed relation whereby said ink transfer means is actuated to operatively engage a printing plate on said 55 impresser bar in advance of the operative

stroke of the latter, a rotatable ink-carrying roll, journaled in fixed position to one side of said impresser bar with which said ink transfer means is initially engaged, transmission means driven from said shaft to 60 rotate said carrying roll, a spreader roll tangent to said ink-carrying roll, and means imparting a longitudinal reciprocating movement to said carrying roll relative to said spreader roll.

3. A device of the kind described, comprising a base; a guide frame having a vertical guideway and a horizontal guideway intersecting the lower end of said vertical guideway, an impresser bar reciprocable in said vertical guideway, means for detachably coupling a printing plate to the lower end of said impresser bar, a yieldable platen block on said base alined beneath said impresser bar, a rotatable shaft 70 journaled in the upper end of said guide frame, an impresser bar actuating cam rotated by said shaft, ink transfer means reciprocable in said horizontal guideway, a bell-crank lever fulcrumed on said guide-frame, means interconnecting the lower end of said lever with said ink-transfer means, an ink transfer means actuating cam rotated by said shaft to operatively engage the upper end of said lever, the active portion of said latter cam operating in advance of the active portion of said impresser bar actuating cam, a rotatable ink-carrying roll journaled in fixed position to one side of said impresser bar with which said ink 75 transfer means is initially engaged, transmission means driven from said shaft to rotate said carrying roll, a spreader roll tangent to said ink-carrying roll, and means imparting a longitudinal reciprocating movement to said carrying roll relative to said spreader roll.

4. A device of the kind described, comprising a base having a guide frame extending upwardly therefrom, a vertically reciprocable printing element mounted on said guide frame, a transversely reciprocable ink transfer means mounted on said guide frame, a rotatable shaft journaled in the upper end of said guide frame, cam devices on said shaft respectively adapted to actuate said printing element and said ink transfer means in timed relation whereby said ink transfer means is operatively moved relative to said printing element in advance of the 100 operative stroke of the latter, and a rotatable ink-carrying roll journaled in said guide frame with which said ink transfer means is initially engaged, and transmission means driven from said shaft to rotate said 105 carrying roll.

5. A device of the kind described, comprising a base having a guide frame extending upwardly therefrom, a vertically reciprocable printing element mounted on 110

- said guide frame, a transversely reciprocable ink transfer means mounted on said guide frame, a rotatable shaft journaled in the upper end of said guide frame, cam devices on said shaft respectively adapted to actuate said printing element and said ink transfer means in timed relation whereby said ink transfer means is operatively moved relative to said printing element in advance 60 of the operative stroke of the latter, a rotatable ink-carrying roll journaled in said guide frame with which said ink transfer means is initially engaged, transmission means driven from said shaft to rotate 65 said carrying roll, a spreader roll tangent to said ink-carrying roll, and means imparting a longitudinal reciprocating movement to said carrying roll relative to said spreader.
- 15 6. A device of the kind described, comprising a base having a guide frame extending upwardly therefrom, a vertically reciprocable printing element mounted on said guide-frame, a yieldable platen, block 70 fixed on said base beneath said printing element, a slide-block transversely reciprocable on said guide-frame, a spring pressed pivoted yoke-frame mounted on said slide-block, ink transfer rolls journaled in the free end of 75 said yoke-frame, a bell-crank lever fulcrumed on said guide-frame, means interconnecting the lower end of said lever with said slide-block, a shaft journaled in the upper end of said guide-frame, cam devices on said shaft respectively adapted to 80 actuate said printing element and said bell-crank lever, said cam devices being set on said shaft in timing relation whereby said slide-block is reciprocated in advance of the reciprocation of said printing element, a rotatable ink-carrying roll journaled in said guide-frame with which said ink transfer 85 rolls are initially engaged, and transmission means driven from said shaft to rotate said carrying roll.
- 20 7. A device of the kind described, comprising a base having a guide frame extending upwardly therefrom, a vertically reciprocable printing element mounted on said guide-frame, a yieldable platen-block fixed on said base beneath said printing element, a slide-block transversely reciprocable on 90 said guide-frame, a spring pressed pivoted yoke-frame mounted on said slide-block, ink transfer rolls journaled in the free end of said yoke-frame, a bell-crank lever fulcrumed on said guide-frame, means interconnecting the lower end of said lever with said slide-block, a shaft journaled in the upper end of said guide-frame, cam devices on said shaft respectively adapted to 95 actuate said printing element and said bell-crank lever, said cam devices being set on said shaft in timing relation whereby said slide-block is reciprocated in advance of the reciprocation of said printing element, a rotatable ink-carrying roll journaled in said guide-frame with which said ink transfer 100 rolls are initially engaged, transmission means driven from said shaft to rotate said carrying roll, a spreader roll tangent to said ink-carrying roll, and means imparting a longitudinal reciprocating movement to said carrying roll relative to said spreader.
- 25 8. A device of the kind described, comprising a base having a guide frame extending upwardly therefrom, a vertically reciprocable printing element mounted on said guide-frame, a yieldable platen-block fixed on said base beneath said printing element, a slide-block transversely reciprocable on 105 said guide-frame, a spring pressed pivoted yoke-frame mounted on said slide-block, ink transfer rolls journaled in the free end of said yoke-frame, a bell-crank lever fulcrumed on said guide-frame, means interconnecting the lower end of said lever with said slide-block, a shaft journaled in the upper end of said guide-frame, cam devices on said shaft respectively adapted to 110 actuate said printing element and said bell-crank lever, said cam devices being set on said shaft in timing relation whereby said slide-block is reciprocated in advance of the reciprocation of said printing element, a rotatable ink-carrying roll journaled in said guide-frame with which said ink transfer 115 rolls are initially engaged, and transmission means driven from said shaft to rotate said carrying roll.
- 30 9. A device of the kind described, comprising a base having a guide frame extending upwardly therefrom, a vertically reciprocable printing element mounted on said guide-frame, a yieldable platen-block fixed on said base beneath said printing element, a slide-block transversely reciprocable on 120 said guide-frame, a spring pressed pivoted yoke-frame mounted on said slide-block, ink transfer rolls journaled in the free end of said yoke-frame, a bell-crank lever fulcrumed on said guide-frame, means interconnecting the lower end of said lever with said slide-block, a shaft journaled in the upper end of said guide-frame, cam devices on said shaft respectively adapted to 125 actuate said printing element and said bell-crank lever, said cam devices being set on said shaft in timing relation whereby said slide-block is reciprocated in advance of the reciprocation of said printing element, a rotatable ink-carrying roll journaled in said guide-frame with which said ink transfer 130 rolls are initially engaged, and transmission means driven from said shaft to rotate said carrying roll.
- 35 10. A device of the kind described, comprising a base having a guide frame extending upwardly therefrom, a vertically reciprocable printing element mounted on said guide-frame, a yieldable platen-block fixed on said base beneath said printing element, a slide-block transversely reciprocable on 135 said guide-frame, a spring pressed pivoted yoke-frame mounted on said slide-block, ink transfer rolls journaled in the free end of said yoke-frame, a bell-crank lever fulcrumed on said guide-frame, means interconnecting the lower end of said lever with said slide-block, a shaft journaled in the upper end of said guide-frame, cam devices on said shaft respectively adapted to 140 actuate said printing element and said bell-crank lever, said cam devices being set on said shaft in timing relation whereby said slide-block is reciprocated in advance of the reciprocation of said printing element, a rotatable ink-carrying roll journaled in said guide-frame with which said ink transfer 145 rolls are initially engaged, and transmission means driven from said shaft to rotate said carrying roll.
- 40 11. A device of the kind described, comprising a base having a guide frame extending upwardly therefrom, a vertically reciprocable printing element mounted on said guide-frame, a yieldable platen-block fixed on said base beneath said printing element, a slide-block transversely reciprocable on 150 said guide-frame, a spring pressed pivoted yoke-frame mounted on said slide-block, ink transfer rolls journaled in the free end of said yoke-frame, a bell-crank lever fulcrumed on said guide-frame, means interconnecting the lower end of said lever with said slide-block, a shaft journaled in the upper end of said guide-frame, cam devices on said shaft respectively adapted to 155 actuate said printing element and said bell-crank lever, said cam devices being set on said shaft in timing relation whereby said slide-block is reciprocated in advance of the reciprocation of said printing element, a rotatable ink-carrying roll journaled in said guide-frame with which said ink transfer 160 rolls are initially engaged, and transmission means driven from said shaft to rotate said carrying roll.
- 45 12. A device of the kind described, comprising a base having a guide frame extending upwardly therefrom, a vertically reciprocable printing element mounted on said guide-frame, a yieldable platen-block fixed on said base beneath said printing element, a slide-block transversely reciprocable on 165 said guide-frame, a spring pressed pivoted yoke-frame mounted on said slide-block, ink transfer rolls journaled in the free end of said yoke-frame, a bell-crank lever fulcrumed on said guide-frame, means interconnecting the lower end of said lever with said slide-block, a shaft journaled in the upper end of said guide-frame, cam devices on said shaft respectively adapted to 170 actuate said printing element and said bell-crank lever, said cam devices being set on said shaft in timing relation whereby said slide-block is reciprocated in advance of the reciprocation of said printing element, a rotatable ink-carrying roll journaled in said guide-frame with which said ink transfer 175 rolls are initially engaged, and transmission means driven from said shaft to rotate said carrying roll.
- 50 13. A device of the kind described, comprising a base having a guide frame extending upwardly therefrom, a vertically reciprocable printing element mounted on said guide-frame, a yieldable platen-block fixed on said base beneath said printing element, a slide-block transversely reciprocable on 180 said guide-frame, a spring pressed pivoted yoke-frame mounted on said slide-block, ink transfer rolls journaled in the free end of said yoke-frame, a bell-crank lever fulcrumed on said guide-frame, means interconnecting the lower end of said lever with said slide-block, a shaft journaled in the upper end of said guide-frame, cam devices on said shaft respectively adapted to 185 actuate said printing element and said bell-crank lever, said cam devices being set on said shaft in timing relation whereby said slide-block is reciprocated in advance of the reciprocation of said printing element, a rotatable ink-carrying roll journaled in said guide-frame with which said ink transfer 190 rolls are initially engaged, and transmission means driven from said shaft to rotate said carrying roll.

Witnesses:

FREDK. C. FRAENTZEL,
EVA E. DESCH.

In testimony, that I claim the invention set forth above I have hereunto set my hand this 7th day of September, 1922.

CHARLES MANSHEL.
